Sons Co., Newark, N.J., a corporation of New Jersey

Filed May 4, 1962, Ser. No. 69,975

Term of patent 14 years

(Cl. D22—4)

FIG. 1 is a front elevational view of a pair of pruning shears showing my new design;

FIG. 2 is a side elevational view thereof as seen from the right of FIG. 1;

FIG. 3 is a side elevational view as seen from the left of FIG. 1 with a portion of the blade omitted for purposes of illustration; and

FIG. 4 is a sectional view taken on line IV-IV of FIG. 1.

The dominant feature of my design resides in the full lines shown in the drawings.

I claim:

The ornamental design for pruning shears as shown.
